UNITED STATES PATENT OFFICE.

JOHN F. MACKIN, OF PHILADELPHIA, PENNSYLVANIA, ASSIGNOR, BY MESNE ASSIGNMENTS, TO LAWRENCE MAXWELL, OF CINCINNATI, OHIO.

REROLLING MECHANISM FOR MUSICAL INSTRUMENTS.

1,154,189.

Specification of Letters Patent. Patented Sept. 21, 1915.

Application filed April 21, 1910. Serial No. 556,658.

To all whom it may concern:

Be it known that I, JOHN F. MACKIN, a citizen of the United States, residing at Philadelphia, in the county of Philadelphia and State of Pennsylvania, have invented 5 a new and useful Rerolling Mechanism for Musical Instruments, of which the following is a specification.

This invention relates to a re-rolling device for a musical instrument controlled 10 by a perforated music sheet.

The principal objects of the invention are to furnish practicable means for automatically reversing the rolling apparatus when 15 the music sheet is almost entirely unrolled from the music roll so as to cause the same to be automatically re-rolled after the selection is played; to provide means for automatically stopping the motor when the 20 roll has been rewound; and to provide for accomplishing these results without the use of any extra perforations, or cuts either in the tracker or music sheet.

Further objects and advantages of the 25 invention will appear hereinafter.

Reference is to be had to the accompanying drawings in which—

Figure 1 is a front elevation of a tracker box showing other parts of a musical instrument partly in diagrammatic form. 30 Fig. 2 is a transverse sectional view of the tracker box. Fig. 3 is an elevation of one of the rolls and connected parts on an enlarged scale. Fig. 4 is an elevation of part 35 of the rerolling connections. Fig. 5 is an elevation of the parts shown at the bottom of Fig. 1, and Fig. 6 is a front elevation of the same on enlarged scale with parts in section.

40 The instrument is shown as having a tracker box 10 provided as usual with a music spool or roll 11 having spindles 12 and with a take-up spool or roll 13 having a gear 14. The shaft 15 for operating 45 the music and take-up spools is operated in any desired way. It is provided with a pinion 16 meshing with the gear 14 for operating the take-up roll and is also provided with a sprocket wheel 17 which operates a 50 sprocket wheel 18 on the spindle 12 and which is designed to be put into operation to re-roll by means of a link 19 for moving a clutch 20 as is well understood in this art. This link is operated by a pneumatic

motor 21 in a way which will be described 55 hereinafter.

Extending through the top of the tracker box or music cabinet is a tube 25 which may be of metal through which extend two wires 26 forming part of an electric circuit. This 60 tube is pivoted on a pin 27 so as to be free to swing and extends beyond the pivot far enough to form a counter-balance, to hold its end against the paper on the spool. It is provided at its lower end with a short insulating member 28 of wood or other non-conducting material shown as of cylindrical form. This is attached by means of a screw or pivot 29 longitudinally located with respect to the tube 25 so that it can have a 70 slight turning motion thereon. On the cylindrical insulating member 28 are two metallic rings 30 insulated from each other by the wooden cylinder, each connected with one of the wires 26. 75

On the music spool is a thin flexible tight-fitting band or contact piece 31 of copper or other conducting material. This band may be removed or put on any music spool very easily without in any way cutting or impairing the spool or the paper. Obviously, it serves to complete the electric circuit between the two rings 30, when the music sheet has been unwound sufficiently to allow the two conducting rings 30 to come down on 85 the spool. This results in establishing a current through a battery 40 and electromagnet 41. This magnet is provided with a leather-faced metallic armature 42 which is moved by the energizing of the magnet 90 away from a port 43 so as to permit air to enter the same. This raises a diaphragm 44, the other side of which is in communication with an exhaust chamber 45. This in turn raises a double valve 46 and brings 95 a passage 47 into communication with the chamber 45 through a port 48 and closes a port 49 to the outside air. This connects the exhaust chamber 45 with the bellows 21 and collapses the same which then operate 100 the link 19 in an obvious manner to connect up the driving shaft 15 with the spindle 12 so as to operate the re-rolling mechanism.

On the bottom of the tracker box is a tube 50 similar to the pivoted tube 25 and having an insulating roll 51 on the end provided with two metallic rings 52. This is adapted 105 to be held away from the take-up spool 13

by the paper but is counterbalanced so as to come into contact therewith when the paper is unwound, as shown in Fig. 1. At this time the two metallic rings 52 come into contact with a metallic contact piece 53 on the take-up spool which may extend all the way, or only part way, around the spool, as desired. If it extends only part way around it should have a certain relationship to the hook 54 which engages the eye in the end of the music sheet, so that it will be in position to engage the rings 52 when the expiring end of the music sheet is in the desired position. When the sheet is entirely re-rolled, an electric contact is made at this point which completes an electric circuit 55, the two terminals of which are the rings 52, and energizes a magnet 56. This magnet operates to raise an armature 57 to release a knife blade switch 58 to permit a spring 59 to draw it out and break the contact, thus breaking a motor circuit 60, which is connected with the motor 61, that operates the shaft 15.

When it is desired to start the machine, a knob 62 is pressed against the spring 59 which brings the knife blade switch into position to make the circuit. It is then held in that position by the gravity armature 57 in an obvious manner. The operation will be obvious.

A music spool 11 is inserted in the cabinet preparatory to playing, with its hook or eye in engagement with the hook 54. The button 62 is then pressed and the motor circuit is thus completed, thus starting the spool 13 into rotation. The first revolution of the spool brings the music sheet between the contact plate 53 and the rings 52 so that the armature 57 will drop to hold the knife-blade-switch in closed position so that the finger can be removed from the button 62. The music sheet continues to wind up on the take-up spool until the selection has been played. At this point the music sheet on the spool 11 uncovers the contact piece 53 thereby completing the electrical circuit 55 and connecting the bellows 21 with the exhaust, as has been explained. This operates the re-roll connections and the music sheet starts back so as to rewind on the music spool 11. As the last turn of the music sheet leaves the spool 13 it uncovers the contact piece 53 and the rings 52 come into engagement with it so as to complete the electrical circuit 55. This raises the armature 57 which permits the spring 59 to act to break the motor circuit and stop the motor.

While I have illustrated and described a preferred embodiment of the invention, I am aware that many modifications can be made therein by any person skilled in the art without departing from the scope of the invention as expressed in the claims. Therefore I do not wish to be limited to all the

details of construction shown and described, but

What I do claim is:—

1. As an article of manufacture, a non-conducting music spool for a musical instrument, said spool having a metallic electrical conducting plate thereon located entirely between the ends of the spool so as to be covered by the music sheet at all times during playing and to be uncovered by the sheet only when the sheet is substantially unwound from the spool.

2. The combination with a non-conducting rotatable take-up spool having a metallic contact piece thereon, of a pivoted arm having two electric terminals thereon insulated from each other and engaging the sheet on the spool, a circuit connected with said terminals, and means in said circuit for controlling the stopping of the rotation of said spool.

3. In a musical instrument, the combination of a music spool, a take-up spool, a note sheet, a shaft, and means for connecting the shaft either with the take-up spool or the music spool, with electro magnetic means supported independent of the note sheet whereby when the note sheet is unwound from the music spool the said connecting means will be operated to connect the shaft with the music spool, and electro magnetic means independent of the note sheet whereby when the note sheet leaves the take-up spool the shaft will be stopped.

4. In a musical instrument, the combination of a music spool having a metallic contacting member thereon in position to be covered by the music sheet at all times when the latter is wound upon the spool, a pair of contact members insulated from each other in position to engage the said contact member when the music sheet is unrolled therefrom, and means electrically controlled thereby for reenrolling the sheet on the spool.

5. In a musical instrument, the combination of a motor, a music spool, pneumatic means for connecting the motor with the music spool to rewind the sheet thereon, electro-magnetic means for controlling the operation of said pneumatic means, an electrical circuit for energizing the electro magnetic means having two terminals normally insulated from each other and located in position to engage the music spool, and means on the music spool for electrically connecting said terminals when the music sheet is unrolled therefrom and they come into contact therewith.

6. In a musical instrument, the combination of a shaft, a music spool, means for connecting the shaft with the music spool for rewinding the sheet on the music spool, a pneumatic having means for operating said connecting means, an electromagnet having an armature, an air conduit nor-

when the terminals are electrically connected, a motor circuit, a switch in the motor circuit, a spring for normally opening said switch, an armature for said magnet having means for holding the switch closed against the action of said spring and arranged to move into a position to release the switch when attracted by the electromagnet, and means on the take-up spool for connecting said terminals and thus completing the

motor circuit when the music sheet is unwound from said spool to expose the last named means.

In testimony whereof I have hereunto set my hand, in the presence of two subscribing 15 witnesses.

JOHN F. MACKIN.
